UNITED STATES PATENT OFFICE.

ROSWELL D. GRANT, OF CHICAGO, ILLINOIS, ASSIGNOR TO THE PYLE-NATIONAL COMPANY, OF CHICAGO, ILLINOIS, A CORPORATION OF NEW JERSEY.

BURNISHING-MACHINE.

1,368,794.

Specification of Letters Patent. Patented Feb. 15, 1921.

Application filed April 12, 1920. Serial No. 373,053.

To all whom it may concern:

Be it known that I, ROSWELL D. GRANT, a citizen of the United States, residing at Chicago, in the county of Cook and State of Illinois, have invented a certain new and useful Improvement in Burnishing-Machines, of which the following is a specification.

My invention relates to a burnishing machine and has for one object to provide a mechanism which will polish and burnish reflectors which are designed for use in headlights and the like. Another object of my invention is to provide a mechanism which may be used to burnish the interior of cup shaped articles in general. Other objects will appear from time to time throughout the specification and claims of my invention wherein:

Figure 1 is a side elevation with parts in section and parts broken away;

Fig. 2 is a vertical section on line 2—2 of Fig. 1;

Fig. 3 is a vertical section along the line 3—3 of Fig. 1.

Like parts are designated by like characters throughout.

A is a supporting table or frame having the supporting legs A¹ A¹. Upon it is mounted the frame A² near the top of which are secured the arc shaped supporting members A³ A³. On them are mounted the lateral carrying members A⁴ A⁴. A⁵ A⁵ are horizontal supporting arms which are secured to the lateral members A⁴ A⁴. B is a driving shaft mounted in the upper end of the frames A² A². B¹ is a pulley upon it adapted to be driven by the belt B² from any suitable source of power not here shown. B³ is a crank disk secured to one end of the shaft B. B⁴ is an eccentric secured at the other end of the shaft B. B⁵ is a reach rod fastened to the eccentric B⁴ and having pivoted at its lower end a lever B⁶ which is also mounted for rotation on the secondary driving shaft C. B⁷ is a pawl pivoted on the arm B⁶ and adapted to engage the ratchet wheel B⁸ mounted on the shaft C and through it to rotate the shaft C in response to the movement of the eccentric B⁴.

50 The shaft C is carried in bearings C¹ C¹ mounted adjacent the surface of the supporting frame A. On it are mounted two worms C² C² in mesh with the worms C³ C³ which are mounted at the lower ends of the shafts 55 C⁴ C⁴. The shafts C⁴ C⁴ are suitably sup-

ported in bearings C⁵ C⁵ which carry in their upper ends supporting frames C⁶ C⁶ adapted to carry the reflectors D D which may be secured in them by the clamps D¹ D¹. By means of the motion imparted by the 60 shaft C and through the worms to the shafts C⁴, the carrying frames with the reflectors mounted in them are slowly rotated.

E E are shafts mounted in opposite ends of the machine. Each has fixed upon it the 65 crank arm E¹ which are connected by means of the reach rod E² to the crank disk B³. By means of the movement of said crank disk each of said shafts E E is caused to oscillate. F F are crank arms mounted adjacent the ends of the shafts E E and adapted to oscillate with it. In each of them is adjustably mounted a supporting member F¹ in which is adjustably mounted a carrying rod F². In the forward end of said carrying rods F² is mounted the polishing tool F³ which has the polishing point or surface F⁴ which may be made of bloodstone or any suitable polishing material. Attached to the rods F² F² are the connecting rods F⁵ F⁵ 80 mounted for oscillation to the members A⁵ A⁵. The rods are surrounded by the coil springs F⁶ F⁶ by means of which they hold the polishing tool in contact with the surface to be polished.

In conjunction with the crank arms F F are clutches G G by means of which the arms may be caused to oscillate with the shaft E or may be thrown out of operation at the will of the operator. The clutch controlling member G¹ is secured to the shaft G² which is carried in any suitable bearing as for example G³ G³. Keyed to the shaft G² is the controlling handle G⁴ which is pivoted on the table A at G⁵. Any suitable 90 arrangement not here shown may be used to hold this controlling handle in the position in which the operator wishes to have it.

H H are trays beneath the reflectors. To them are connected the troughs H¹ H¹ which extend upward beneath the reflectors and carrying frames. During the burnishing process it is often desirable to apply a lubricant to the surface of the reflector and it is the purpose of these troughs and trays to 100 carry the lubricant as it flows from the reflector. The lubricant may be applied to the surface of the reflector in any suitable manner not here shown as it forms no part of my invention.

Although I have shown in my drawings an operative form of my invention, still it will be obvious that many changes both in form, size and relation of parts might be made without departing from the spirit of my invention. I wish therefore that my drawings be taken as in a sense diagrammatic.

The use and operation of my invention 10 are as follows:

Reflectors or the like to be burnished are secured in the carrying frames by means of the clamps. The polishing or burnishing tools are then positioned with the working 15 surface of the tool in contact with the face of the reflector. The machine is then put in operation and the carrying frame with the reflectors are slowly rotated step by step through the ratchet and pawl. At the same 20 time the burnishing tool is moved back and forth across the surface of the reflector from the center to the edge. In this manner every part of the surface is progressively brought in contact with the burnishing tool and is thus burnished. During this process any 25 suitable lubricant may be applied to the surface of the reflector in the usual manner.

Claims:

1. In a burnishing machine, a work holding frame mounted for rotation, means for rotating it step by step and a burnishing tool adapted to oscillate across the surface of the work during said rotation.
2. In a burnishing machine, a work holding frame mounted for rotation, means for rotating it step by step, said means including a ratchet and pawl, a burnishing tool adapted to oscillate across the surface of the work during said rotation, and means for oscillating said burnishing tool.
3. In a burnishing machine, a work holding frame mounted for rotation, means for rotating it step by step, said means including a ratchet and pawl, a burnishing tool adapted to oscillate across the surface of the work during said rotation, and means for oscillating said burnishing tool, a unit driving means adapted to operate said tool and to rotate said work holding frame.
4. In a burnishing machine, a work holding frame mounted for rotation, means for rotating said frame step by step, said means comprising a driven shaft, a second shaft, means for driving said second shaft, step by step, said means including a ratchet and pawl, worms on said second shaft, worms connected to said holding frame and adapted to cause said frame to rotate in response to the rotation of said second shaft.
5. In a burnishing machine, a work holding frame mounted for rotation, means for rotating it step by step and a burnishing tool adapted to oscillate across the surface of the work during said rotation, means for oscillating said tool comprising a driven

shaft, a crank disk on said shaft, a shaft mounted for oscillation, a crank arm on said shaft and connected to said crank disk, additional crank arms on said shaft, a tool carrying member adjustably mounted in said arms, a burnishing tool mounted in the end of said arms, including spring controlled means for supporting said tool holding arm and for holding said tool in contact with said worms.

6. In a burnishing machine, a work holding frame mounted for rotation, means for rotating it step by step, said means including an eccentric, a ratchet and pawl, a burnishing tool adapted to oscillate across the surface of the work during the rotation of said frame and means for oscillating said burnishing tool.

7. In a burnishing machine, a plurality of work holding frames mounted for rotation, means for rotating them step by step, a plurality of burnishing tools adapted to oscillate across the surface of the work during the rotation of said frames and means for oscillating said burnishing tools.

8. In a burnishing machine, a plurality of work holding frames mounted for rotation, means for rotating them step by step, a plurality of adjustably mounted burnishing tools adapted to oscillate across the surface of the work during the rotation of said frames and means for oscillating said burnishing tools.

9. In a burnishing machine, a plurality of work holding frames mounted for rotation, means for rotating them step by step, a plurality of adjustably mounted burnishing tools adapted to oscillate across the surface of the work during the rotation of said frames, means for oscillating said burnishing tools and means for adjusting the amount of travel of said burnishing tools.

10. In a burnishing machine, a plurality of work holding frames mounted for rotation, means for rotating them step by step, a plurality of burnishing tools adapted to oscillate across the surface of the work during the rotation of said frames, means for oscillating said burnishing tools, and means for rotating said frames and operating said tools in unison.

11. In a burnishing machine, a plurality of work holding frames mounted for rotation, means for rotating them step by step, a plurality of burnishing tools adapted to oscillate across the surface of the work during the rotation of said frames, means for oscillating said burnishing tools, means for rotating said frames and operating said tools in unison, and means for throwing out of operation one or more of said tools at the will of the operator.

12. In a burnishing machine, a plurality of work holding frames mounted for rotation, means for rotating them step by step,

a plurality of burnishing tools adapted to oscillate across the surface of the work during the rotation of said frames, means for oscillating said burnishing tools, means for 5 rotating said frames and operating said tools in unison and means for varying the speed of rotation of said work carrying frames.

13. In a burnishing machine, a plurality 10 of work holding frames mounted for rotation, means for rotating them step by step, a plurality of burnishing tools adapted to oscillate across the surface of the work during the rotation of said frames, means for 15 oscillating said burnishing tools, means for rotating said frames and operating said tools in unison, means for throwing out of operation one or more of said tools at the will of the operator and means for varying the speed 20 of rotation of said work carrying frames.

14. In a burnishing machine, a work holding frame mounted for rotation, means for rotating it step by step, and a burnishing tool adapted to oscillate across the surface of the work during said rotation, and adapted 25 to make an excursion across the surface of said work between each step in the rotation of the work.

15. In a burnishing machine, a work holding frame mounted for rotation, means for 30 rotating it step by step, and a burnishing tool adapted to oscillate across the surface of the work, making an excursion in one direction between each step of the rotation of said work, and an excursion in the opposite 35 direction during such step.

Signed at Chicago, county of Cook and State of Illinois, this 30th day of March, 1920.

ROSWELL D. GRANT.
